United States Patent Office

Des. 233,950
Patented Dec. 17, 1974

233,950

PRINTER

Gary R. Bluem, Minneapolis, Minn., assignor to
Kroy Industries, Inc., Stillwater, Minn.

Filed Mar. 26, 1973, Ser. No. 345,080

Term of patent 14 years

Int. Cl. D18—02

U.S. Cl. D64—11 R

Fig. 1

Fig. 2

Fig. 3

FIG. 1 is a perspective view of a printer showing my new design;

FIG. 2 is a left side elevational view; and

FIG. 3 is a top plan view.

The side panel not shown is a mirror image of left side panel.

I claim:

The ornamental design for a printer, as shown and described.
